UNITED STATES PATENT OFFICE.

RICHARD BLAIR COOPER, OF NEW YORK, N. Y., ASSIGNOR TO FISKE & COMPANY, INC.,
OF BOSTON, MASSACHUSETTS, A CORPORATION OF MASSACHUSETTS.

BRICK.

Application filed February 19, 1921. Serial No. 446,438.

To all whom it may concern:

Be it known that I, RICHARD B. COOPER, a citizen of the United States, and resident of Bronx, New York, county of Westchester, 5 and State of New York, have invented an Improvement in Bricks, of which the following description, in connection with the accompanying drawings, is a specification, like letters on the drawings representing 10 like parts.

My present invention is an improved hollow wall structure and a type of channel brick therefor, suitable for handling and building a fire proof hollow wall giving the 15 external appearance of standard brick construction.

In my present invention, I have developed an improved form of channel brick, which is of extremely simple construction, and great 20 strength and which is also particularly designed for ease in handling and speed in laying up in the wall. In carrying out the invention I provide a double or twin wall block with a plurality of horizontally extending air spaces through the wall sections, together with one or more mortar receiving 25 recesses and air channels so that the horizontal mortar courses will be interrupted—thus insuring moistureproofness in the completed 30 wall—and yet giving a relatively large and firm bearing space or “bed” for the mortar in each wall section. In the preferred form of my present channel brick I make the wall sections of relatively large and proportionately greater area in cross section than 35 that theretofore customary with the commercial manufacture of channel brick. This feature gives me the important advantages of having a very strong and heavy exterior 40 web or portion at the exposed faces of the brick and consequently of the wall, thus insuring load carrying, fire-proofing and strength. Where the wall sections in such a small building unit as that of a bricksized 45 article, i. e., a “twin wall” “channel brick,” it is important and necessary to have the “cored” portions in the wall sections of substantial area in order to provide lightness and therefore the webs, ribs, etc., constitute the solid portions of the clay around the cored sections, and are relatively light. In the case of fire and intense heat, the air 50 inside these horizontal cored sections is apt to burst, by expansion, the ribs or webs. 55 On the other hand, to make the walls, ribs

or webs of great thickness would add to the weight and would reduce the cored area in the wall section to so small a proportion as to render it difficult to manufacture, unsatisfactory in drying and burning and negligible in weight saving. One of the 60 advantageous features of my present channel brick is that I am enabled to make the wall sections of my twin wall channel brick relatively large and thereby to still obtain 65 the advantages of lightness in weight, simplicity and ease in manufacture, drying, and burning, and still to give a substantial thickness at the outer web portions.

A further important feature of my present twin wall channel brick consists in the fact that by having a twin wall section relatively large and of a considerable proportion widthwise of the brick, I am enabled to take advantage of either wall section to constitute the handhold or gripping part of the building unit. This feature is of special importance and eliminates the prior difficulty in articles of this type wherein the workman was obliged to extend his hand to grasp 70 ribs or the like in opposite wall sections in order to lift and handle the brick. My present invention and improved form of channel brick, wherein the wall sections themselves are of such large area and—preferably—the 75 center channel or air space is of relatively small area, enables the workman to handle the entire brick by grasping one of the wall sections alone. Heretofore all channel brick, in order to be handled by the mason, have 80 been made with the object of providing balanced gripping capabilities, i. e., with a plurality of means equally spaced with relation to the central air channel of the brick, which air channel the mason must span with 85 his hand in order to grasp or hold the brick or be obliged to take two hands to same. My present invention presents a structure which eliminates this difficulty and which provides a channel brick capable 90 of being handled by a non-balanced or eccentric grip or handhold. This feature I believe to be a distinct novelty in this art and I wish to claim the same broadly. By providing means in each wall section so 95 that the mason can grasp the same and readily handle the entire building unit, increased speed and ease of operation in channel brick wall building is provided; the channel brick can be stored or stood on 100 105 110

edge and readily grasped and moved into position, the mason settling the same on the mortar bed prepared for it and forcing it downwardly, the broad relatively large wall section which he utilizes as a handhold being also in position to receive the weight and pressure of the mason when settling the brick and alining it. It is a much simpler, easier and speedier operation of building a channel wall structure when the mason has thus hold of the exposed face or outer wall section which he is alining and positioning, truing up the same with the adjacent courses, abutting piers or other parts of the structure.

In order to facilitate the eccentric handhold feature I prefer to form the inner edge portions of each wall section and those abutting on the central air space, with an overhanging portion to facilitate the finger gripping capability for a handhold on each wall section. This still further aids in giving me the provision of a broad mortar receiving surface on each wall section. Thus a substantial mass of mortar for the wall sections and load carrying strains in the wall is supplied and yet a very light building unit with relatively large and therefore efficient air spaces through the wall sections, as well as through the center, is produced.

I may make my present improved form of channel brick either with a plurality of mortar receiving recesses in top and lower faces or with projecting lugs as interlocking or moisture check features, both these forms being shown in the drawings, or with various other modifications, but I believe that a channel brick of the kind described, with sufficiently large wall sections to afford a non-balanced or eccentric grip or handhold, is a distinct novelty, and so long as this feature is present, my invention is carried out.

It will be appreciated that my channel brick combines the important and desirable functions of a twin wall structure, having a plurality of horizontal air spaces for insulation against the transference of heat or cold through the wall, utilizing one or more types of interlocking features, employing the channel brick idea of an interrupting space for the mortar course, having all vertical ribs or webs in alinement for load carrying strength, preferably presenting the mortar retaining grooves and riblike ridges, as well as the light weight of the several standard types of channel brick covered by said prior patents. In addition thereto I have devised a channel brick which has a strong and load carrying outer web face preventing bursting during intense heat, and in effect allowing for a solid fire-resisting face at each edge of the wall, together with an extra large mortar bed on each wall section, insuring the central air recess interrupting the mortar joint, and the further novelty and

advantages of the eccentric handhold above explained.

Referring to the drawings, illustrating preferred embodiments of the invention,

Fig. 1 is a cross-sectional view of one form 70 of my twin wall channel brick;

Fig. 2 is a fragmentary perspective view of a wall structure made of the brick of Fig. 1;

Fig. 3 is a modified form of my twin wall 75 channel brick having interlocking lugs; and

Fig. 4 is a fragmentary perspective view of a wall structure with the interlocking lugs of different size, some affording a positive interlock and other lugs giving only a 80 mortar interlock and moisture checking feature in the wall.

As shown in Figs. 1 and 2 my channel brick may be formed of clay material in a continuous manufacturing operation by utilizing a die, wire cut off, etc., and presents two wall sections, united by a central body portion 1. The wall sections are preferably duplex in order to be interchangeable and reversible—it being immaterial which side 90 or end is set up in the wall. Furthermore these building units are reversible upside down, i. e., may be either built into a wall as shown in Fig. 2, or set reversely, as is illustrated by inverting the drawing. These 95 wall sections I have designated generally as 2 and each comprises a vertical outer web face 5, an inner vertical riblike member or portion 6 and top webs 7 and bottom webs 8, each enclosing the cored or horizontal air 100 space 10. These wall sections form a central air channel 12 adapted to interrupt the mortar course and preferably also I form a cooperating recess 13 on the other side of the central web 1 which will enlarge the 105 inner mortar interrupting part designated at 15 in Fig. 2. The recess 13 of one brick cooperating with the central channel 12 of the next adjacent brick to form the area 15.

The outer faces of the brick 5 are preferably of sufficient thickness to take care of all strains incurred and be a solid, fire-resisting wall, preventing bursting by swelling of the confined air in the cored sections 10. This face is also of a size and area to simulate standard brick and to interlock with common or standard brick at corners, piers or the like throughout the wall structure.

To facilitate the handling of the brick and to provide the non-balanced or eccentric handhold, I prefer to form the top inner edges of each wall section adjacent the open air channel 12 with an overlapping or finger holding projection 16. The wall sections also are of sufficient extent or proportion, cross-wise of the channel brick, to constitute a convenient and firm hold, when the mason grips one of the wall sections. The top and bottom parts of each wall section may be, and preferably are, recessed at 130

18 for increased lightness, to give a mortar retaining recess and corresponding ribs, and serving also as an interlock with the mass of mortar 20 constituting this part of the 5 mortar course, which will find its way into the adjacent recesses and thus the surplus mortar in the mortar course be utilized and largely prevented from falling over into the central channel 15 in building the wall.

10 In Figs. 3 and 4 I have illustrated a modified form wherein this channel brick has a body portion 25, twin wall sections 26, 26, and the cored centers 27, 27, as well as the central air space or channels 28 and 29, substantially identical with that form shown in 15 Figs. 1 and 2 and already described. On this form of channel brick, however, I have illustrated a pair of interlocking and projecting lugs 30, 30, extending from each 20 wall section, and adapted to interlock with the corresponding recesses 31, 31, in the adjacent lowermost brick. In this form the mortar course 32 is compressed by the lugs 30 which may afford a mortar interlock as 25 shown at the two lowermost channel brick in Fig. 4 or the said lugs 30 may be enlarged as indicated at 35 in the topmost brick of said Fig. 4 extending into the adjacent recesses 31 and thus giving a positive 30 interlock.

In both forms of my improved channel brick I find that in a brick for an 8" wall, i. e., 8" widthwise from face to face, the wall sections may be and preferably are of 35 approximately $3\frac{1}{4}$ " widthwise or transversely, thus leaving the central air space 12 in one form and 28 in the other, of from about $1\frac{1}{2}$ " between the overhanging finger grip edges of the inner wall portions. This 40 dimension of 3 or $3\frac{1}{4}$ " gives a suitable, satisfactory, firm and easy grip or handhold for the mason, extending almost into the central area of the brick. As the entire brick structure and the wall sections are 45 relatively light, because of the recesses and cored areas, the entire brick structure is thus easily handled without difficulty, undue strain or tiring the mason. The channel brick can be piled and transported, either 50 face up, and be easily and quickly grasped and positioned in the wall. Furthermore, my present channel brick can be manufactured in a most advantageous manner, the design of the brick or block lending itself 55 with peculiar adaptability to manufacturing

either as a double or duplex block from which the two channel brick are cut, or as a single block. When manufactured as a duplex block, the relatively wide and broad surfaces of the wall sections enable the clay 60 to be wire cut when plastic and as it emerges from the die of a brick or tile machine, the broad bearing and contact surfaces permitting immediate and sufficient uniting of the wire cut sections to retain the double channel 65 brick united throughout further transporting, drying and burning, and yet readily being separable or split when desired for use. The broad surfaces of the wall sections also permit ready manufacture as a single block, 70 resting upon the offbearing belt from a die machine, without distortion, and being sufficiently united by the relatively short or narrow body portion, cross web, or tie member 1 or 25, to prevent distortion. An additional advantage of the relatively large 75 wall sections consists in the fact that these wall sections when made as a double block can be properly cored to form the mortar receiving recesses 18 in one form and 31 in 80 the other, without difficulty, these recesses being of substantial area in cross-section, whereas extremely small and minute cores would cause difficulty, undue friction, and unsatisfactory operation in a die machine 85 while also tending to clog, close up, etc.

My invention is further described and defined in the form of claims as follows:

1. A channel brick of the kind described, comprising a plurality of wall sections and 90 a central area connecting the same together, mortar grooves in each wall section, and an overhanging finger grip on the inner edge of each wall section to constitute an eccentric handhold for the brick. 95

2. A building unit of the kind described, comprising a balanced structure including a body portion, twin wall sections on either side thereof, and a handhold eccentric relatively with respect to the center of gravity 100 of the unit.

3. Channel brick of the kind described, comprising a body portion and twin wall sections at opposite faces, a plurality of handholds formed on said wall sections, each 105 handhold being eccentric with relation to the center of the gravity of the brick.

In testimony whereof, I have signed my name to this specification.

RICHARD BLAIR COOPER.
